UNITED STATES PATENT OFFICE

2,369,306

ROTARY ENGINE

Lorin D. McCleary, Indianapolis, Ind.

Application December 31, 1942, Serial No. 470,732

2 Claims. (Cl. 60—13)

This invention relates to a combined rotary and reciprocating type engine involving two oppositely revolving members, each serving as a flywheel, one of the members being driven through a leverage system actuated by pistons within the cylinders of the reciprocating part of the engine, and the other member being driven by reaction forces from said cylinders.

Reference is made to my issued United States Letters Patent, No. 2,359,657, October 3, 1944.

The primary object of this invention is to utilize exhaust gases from the cylinders in such manner as to derive additional power therefrom in further driving of said members.

A further important object of the invention is to provide in an engine of the type indicated, a simplified structure wherein power impulses in different cylinders may be applied simultaneously at different points or zones of revolution of said members.

A still further important object of the invention is to provide an engine of maximum thermal and mechanical efficiencies embodied in a structure delivering a maximum power from a mechanism limited to both a minimum of over-all dimensions and weight. The invention comprises essentially a structure having a plurality of cylinders arranged in groups in opposition one to the other, a piston in each cylinder, connecting rods from the pistons operating separate crank assemblies, two rotatable inertia storage masses in the form of said members as above indicated, a leverage system interconnecting one of said crank assemblies to one of said rotatable members, another leverage system interconnecting the other crank assembly with the other of said rotatable members, and turbine means fixed to one of those rotatable members receiving the exhaust gases from the cylinders carried by the other of those rotatable members.

The invention provides a unique method of not only conducting the exhaust gases from the cylinders carried by an inner rotatable member through the outer rotatable member which circumferentially surrounds the inner member, but also provides means for deriving power therefrom.

These and many other objects and advantages of the invention, including the unique combinations of the elements as set forth in the appended claims, will become apparent to those versed in the art in the following description of one particular form of the invention as illustrated more or less diagrammatically in the accompanying drawings, in which

Fig. 1 is a view in central, vertical, longitudinal section through a structure embodying the invention;

Fig. 2, a view in vertical transverse section on the line 2—2 in Fig. 1;

Fig. 3, a section on the line 3—3 in Fig. 1, on a reduced scale;

Fig. 4, a view in section on the line 4—4 in Fig. 1;

10 Fig. 5, a horizontal transverse section through the left-hand end of the structure on the line 5—5 in Fig. 2; and

Fig. 6, a view in perspective of a cam.

Like characters of reference indicate like parts throughout the several views in the drawings.

A member 10 is rotatably mounted between standards 11 and 12 to turn about a horizontally disposed axis. While the member 10 may assume any desired shape, it preferably is made to have considerable mass in order to serve in the nature of a flywheel. This member 10 is herein shown as a frusto-conical drum, one end of which is centered on and secured to a hollow shaft 13. This shaft 13 has a flange 14 extending annularly therearound and abutting the head of the drum 10 from the inside thereof, the head being secured to this flange by any suitable means, such as by cap screws 15, Fig. 1. The other end of the drum member 10 has a hub 16 secured on the inside of that end and axially thereof. Into this hub 16 is carried a shaft 17 and this shaft 17 extends on out through the standard 12. Fixed to the shaft 17 between the hub 16 and the standard 12 is a shaft driving flange 18, the purpose of which will be explained hereinafter.

The drum member 10 is provided with a pair of spaced apart radially extending walls 19 and 20. Between these walls 19 and 20 are positioned a plurality of blades or buckets 21 regularly spaced apart. This assembly of the walls 19 and 20 with the intervening blades 21 is fixed to the circumferential wall of the drum member 10 about an annular opening therethrough in such manner that passageways are provided between adjacent blades 21 leading from the inside of the member 10 to the outside thereof. An annular housing 22 is provided to surround the outer end portions of the walls 19 and 20 to provide a closed passageway 23 therearound. In the form herein shown, this housing 22 consists of a U-shaped member telescoping with a sliding fit over the walls 19 and 20. This housing member 22 is fixed in position against rotation by any suitable means, such as being secured to the base 24 to

which the standards 11 and 12 are attached. Tangentially mounted discharge pipes 25, herein shown as two in number and diametrically positioned, provide outlets from this passage 23.

An inner frame member 26, of any suitable form limited in shape and size to be inserted within the drum member 10 and herein shown as a frusto-conical drum, is rotatably mounted within the drum member 10. At the left-hand end of the frame member 26, a tubular bearing 27 inturned from the end wall receives a stub end 28 of the shaft 13. The outer face of the end wall of the frame member 26 is in sliding abutment with the inner face of a flange 29 extending radially from the inner end of the shaft 13, this flange 29 being spaced a distance from the flange 14 in order to provide an annular chamber 30 therebetween.

This chamber 30 is circumferentially closed by means of an encircling band 31 fixed to the end of the frame member 26 to slide about the periphery of each of the flanges 14 and 29. Communication between this annular chamber 30 and the bore of the hollow shaft 13 is had by means of a plurality of passageways 32 radially extending through the wall of the shaft 13.

The other end of the frame member 26 has a hub 33 axially secured to the right-hand end wall. This hub 33 is provided with a bore therethrough which engages with a sliding fit around the hub 16.

Within the frame member 26 are mounted a plurality of engine cylinders, herein shown as eight in number, grouped in opposing manner, two upper cylinders 34 and 35 on the one side being aligned with two upper cylinders 36 and 37 while two lower cylinders 38 and 39 are similarly oppositely aligned with cylinders 40 and 41. A crankshaft 42, rotatably carried by the frame member 26, herein shown as by the two spaced apart inner heads 43 and 44, is so mounted as to have its axis of rotation spaced radially from the axis of the frame 26 and to be midway between the two sets of cylinders 34, 35 and 36, 37. Secured to the throws of the crankshaft 42 are connecting rods 45, 46 and 47, 48 interconnecting with pistons in the respective cylinders. In other words, the pistons of these four upper cylinders serve to drive the crankshaft 42.

On the left-hand end of the crankshaft 42 is fixed a crank arm 49. A crank pin 50 is carried by the outer end of the arm 49 and centered thereon at a distance from the axis of rotation of the shaft 42 equal to the distance between that axis and the longitudinal axis of rotation of the frame member 26, this being the axis in common of the two shafts 13 and 17.

A link 51 is rotatably fitted by one end over the pin 50, and by its other end is rotatably engaged through a pin 52 with the crank arm 53 which is fixed to the inner end of the shaft 28, this shaft 28 being, as above explained, a fixed part of the shaft 13. The distance between centers of the pins 50 and 52 exceeds the effective length of the crank arm 49, being substantially twice that amount.

The link 51 carries on its inner face, directed toward the head 43, a cam 54. This cam member 54 has an inner cam surface 55 which is in the path of a pin 56 that is fixed to and extends from the outer face of the head 43. The cam member 54 is also provided with a slot 57 thereacross which is in the path of a pin 58 also fixed to and extending from the outer face of the head 43.

The purpose of this cam member 54 and the two pins 56 and 58 is to carry the connecting link 51

and the crank arm 53 past "dead center," which is that position as indicated in the drawings, Figs. 1, 2 and 5. To carry these two members past this condition is only necessary upon starting the engine since inertia will take care of the situation after the various members are traveling at their operating speeds. This particular structure does not form the gist of the invention in this present case, and is more fully explained in the above indicated patent. It is sufficient to state that as the crank arm 49 is revolved, the cam member 54 will, as indicated, be carried around to cause the pin 58 to enter the slot 57, which slot is so positioned across the cam member, and the pin 56 is so located in reference thereto, that the cam member 54 will be so guided as to push the crank arm 53 on around out of parallel alignment with a line through the link 51 between its pivot point centers. Then when the opposite position of parallel alignment is approached, the inner cam surface 55 will strike toward one end thereof, the pin 56 to cause a like relative shifting between the members 51 and 53.

In like manner, pistons in the lower bank of cylinders 38, 39 and 40, 41 operate through intervening connecting rods to drive the crankshaft 59. This crankshaft 59 is mounted to revolve about an axis diametrically spaced from the axis of the other crankshaft 42, the axis of this crank 59 being at a radial distance from the axis of the shafts 13 and 17 equal to the spacing of the shaft 42 on the other side thereof.

On the right-hand end of the shaft 59 is fixed a crank arm 60, the outer end of which arm is rotatably engaged with the connecting link 61 which is identical in size and shape with the connecting link 51 above described. The distance between the axis of the crankshaft 59 and the center of the pivot of the link 61 on the crank arm 60 equals the radial distance between that shaft 59 and the axis of the shafts 13 and 17. The link 61 carries a cam member 62 identical in size and shape with the cam member 54 and serving the same purpose upon cooperating with the pins 63 and 64, Fig. 3. The outer end of the connecting link 61 is rockably engaged with the outer end of the lever 65 which is fixed to the hub 16. The distance between pivot points of the connecting link 61 is equivalent to the distance between pivot points of the connecting link 51. However, it is to be noted that the crank arm 65 in the position shown in Fig. 1 is 180 degrees from the position of the crank arm 53.

In the description so far given, it is to be noted that the crank arm 53 upon being revolved will drive the shaft 13 and then the outer drum member 10 fixed thereto. In like manner the crank arm 65, through the hub 16, will drive the outer drum member 10, it being remembered that the inner frame member 26 is free to revolve in an opposite direction due to the two lever systems described under the reactive explosion forces set up in the cylinders, tending to move the cylinders in one direction and the pistons in the opposite directions. It is necessary to interconnect the inner frame member 26 in a driving manner with the shaft 17 in order to keep the two members 10 and 26 revolving in timed sequence and in order to furnish a power take-off at the outer end of the shaft 17.

The inner frame member 26 is interconnected with this shaft member 17 through the above indicated flange 18 by an ingenious construction. The hub 33, which supports the right-hand end of the frame member 26 about the hub 16, is pro-

vided with a plurality of slots therethrough, herein shown as two in number and diametrically positioned, through which slots may be reciprocated the dogs 66 and 67. The radial flange extending from the hub 16 and interconnecting with the right-hand end of the drum member 10 is provided with an arcuate slot 68, Fig. 3, this slot being cut through that flange to provide an opening therethrough in the path of the ends of these dogs 66 and 67. The shaft flange 18 is provided with a pair of diametrically positioned openings therein radially spaced to coincide with the slot 68, whereby upon proper relative travel of the hubs 16 and 33, the dogs 66 and 67 may be inserted through the slot 68 into the openings in the flange 18, and one dog at a time withdrawn to secure the solid part of the flange of the hub 16 intervening between the ends of the slot 68.

In order to effect the proper timed reciprocation of the dogs 66 and 67, a groove 69 is provided around the periphery of the hub 16 inclined to the axis thereof, and inner ends, herein shown as balls, of the dogs 66 and 67 engage within this slot. It being remembered that the hub 16 is turning in an opposite direction to that of the hub 33, rotation of those members will cause the dogs 66 and 67 to be reciprocated in directions parallel of the axis of the shaft 17. The inclination of the groove 69 is so aligned with the slot 68 that one dog will always be engaged in an opening in the flange 18 when the other dog is withdrawn and this engagement will remain until the other dog is again inserted in its respective opening. Thus the shaft 17 is driven in the same direction and at the same rate of speed as that of the inner frame member 26.

The frame member 26 is provided with a circumferential wall 26a slidably fitted against the inner edges of the walls 19 and 20 to effect a normal closure therebetween and entirely therearound circumferentially. Exhaust conduits lead from the respective cylinders to discharge through this circumferential wall of the frame member 26 between the walls 19 and 20 to have the gases discharge between the blades 21. In the form herein shown, the four cylinders 34, 35, 38, 39 have their exhaust discharges interconnected to finally discharge through the common pipe 10, Figs. 1 and 2, while the other four cylinders discharge in common through the exhaust pipe 11, Fig. 2, the openings of these two pipes being substantially at diametrically opposite positions around the wall of the frame member 26.

The blades 21 are properly shaped to cause the impingement and expansion of the exhaust gases therein and therebetween to set up a driving force tending to drive the outer drum member 10 in the direction in which it is already turning under the direct driving connections. The relative directions of travel between the outer member 10 and the inner member 26 are indicated by the arrows in Fig. 2. The gases escaping from between the outer ends of the blades 21 may travel around through the passageway 23 to escape through the pipes 25.

No attempt has been made to illustrate cooling and ignition systems since any standard forms thereof may be employed, these parts of the structure being purposely omitted to prevent confusion in the showing of the gist of the invention. It is to be pointed out, however, that a very simple valve operating mechanism is employed in that a single gear 72 mounted on the inner end of the shaft 28 serves to drive the intermeshed bevel gears 73 and 74 respectively fixed on the laterally

extending shafts 75 and 76. The outer ends of these shafts 75 and 76 have fixed thereon respectively the gears 77 and 78 which are in turn meshed with gears 79 and 80 fixed to cam shafts 81 and 82. These cam shafts, as indicated in Figs. 1 and 2, extend centrally between and outside of the heads of the upper and lower banks of cylinders to operate directly rocker arms 83 in turn pressing open the respective cylinder valves. It is desired that the timing of firing of the cylinders be such that at least two diametrically opposed cylinders fire at the same time.

The design of the structure provides for relatively high piston speed with relatively low drive shaft speed, that is the speed of the shafts 13 and 17. In any event, in the structure herein described, when either one of the crankshafts 42 or 59, to which reference may be made, travels through two revolutions, one member 10 or 26 will travel through one revolution when the member is held stationary by fixing one of the drive shafts 13 or 17. In this regard it is to be pointed out that power may be taken simultaneously from both of these shafts (one turning in opposite direction to the other) or one shaft may be held stationary to have the driving power transmitted through the other shaft. If the outer drum member 10 is held stationary by fixing the drive shaft 13, then the driving force is from the reaction of the cylinders in relation to the pistons therein. On the other hand, if the frame member 26 which carries the cylinders is held stationary through the drive shaft 17, then the engine is driven directly from the pistons. When both members 10 and 26 are free to revolve, then the reactionary forces on the cylinders plus the direct drive from the pistons constitutes the two opposing moving forces, one force turning one rotatable member in one direction and the other force turning the other rotatable member in an opposing direction. In other words, an explosion within a cylinder tends to drive the cylinder backwards away from the piston to in turn tend to revolve the inner frame member 26 while the piston is pushing the outer drum member 10 in the other direction. This motive force is augmented by the side pressure of the piston on the cylinder wall due to angularity of the connecting rod.

A fuel supply to the various cylinders is had through the bore of the shaft 13, the passageways 32 into the chamber 30; and through an intake pipe 84 which is carried by the inner frame member 26 and carried inwardly thereof to divide into the two branches 85 and 86 to go to the respective groups of cylinders on each side of the frame member 26.

While I have herein shown and described my invention in the one particular form, it is obvious that structural variations may be employed without departing from the spirit of the invention and I therefore do not desire to be limited to that precise form beyond the limitations as may be imposed by the following claims.

I claim:

1. In a prime mover employing fluid pressures as a source of energy, a rotatable member carrying cylinder and piston assemblies for converting said fluid pressures into mechanical power, a crankshaft journaled to rotate within the plane and orbit of said member and in the opposite direction thereto, members connecting said pistons to crank pins on said crankshaft, means for applying the torque action imparted to said crankshaft and the torque reaction imparted to

said cylinders and member to drive the load imposed upon said prime mover, a second member concentrically rotatable about the first member, turbine blading positioned around the second member; and means conducting from said cylinder and piston assemblies exhaust gases and discharging those gases into said blading, a second unit of cylinder and piston assemblies carried by said first rotatable member, a second crankshaft driven by the pistons of said second unit and journaled to rotate within said first member in the opposite direction of rotation of that member; means drivingly interconnecting said second crankshaft with said second member, reaction members carried by and around said second member; and means conducting exhaust gases from both of said cylinder and piston assemblies to discharge to said reaction members.

2. In a prime mover employing fluid pressures as a source of energy, a rotatable member carrying cylinder and piston assemblies for converting said fluid pressures into mechanical power, a crankshaft journaled to rotate within the plane and orbit of said member and in the opposite direction thereto; members connecting said pis-

tons to crank pins on said crankshaft, means for applying the torque action imparted to said crankshaft and the torque reaction imparted to said cylinders and member to drive the load imposed upon said prime mover, a second member concentrically rotatable about the first member, turbine blading positioned around the second member; and means conducting from said cylinder and piston assemblies exhaust gases and discharging those gases into said blading, a second unit of cylinder and piston assemblies carried by said first rotatable member, a second crankshaft driven by the pistons of said second unit and journaled to rotate within said first member in the opposite direction of rotation of that member; means drivingly interconnecting said second crankshaft with said second member, reaction members carried by and around said second member; and means conducting exhaust gases from both of said cylinder and piston assemblies to discharge to said reaction members, a stationary collector about said reaction means receiving gases passing thereacross, and gas escape means on said collector.

LORIN D. McCLEARY.

CERTIFICATE OF CORRECTION.

Patent No. 2,369,306.

February 13, 1945.

LORIN D. McCLEARY,

It is hereby certified that error appears in the above numbered patent requiring correction as follows: In the drawings, Sheet 2, Figure 2 should appear as shown below instead of as in the patent -

and that the said Letters Patent should be read with this correction therein that the same may conform to the record of the case in the Patent Office.

Signed and sealed this 6th day of November A.D. 1945

Leslie Frazer
